US00D840451S

(12) **United States Design Patent** (10) Patent No.: **US D840,451 S**
 Yoo et al. (45) Date of Patent: ** Feb. 12, 2019

(54) **ROBOT FOR GUIDING PEOPLE**

(71) Applicant: **LG ELECTRONICS INC.**, Seoul (KR)

(72) Inventors: **Joonggil Yoo**, Seoul (KR); **Sangyoon Lee**, Seoul (KR); **Hyunjung Kim**, Seoul (KR); **Soonho Jung**, Seoul (KR)

(73) Assignee: **LG ELECTRONICS INC.**, Seoul (KR)

(**) Term: **15 Years**

(21) Appl. No.: **35/503,953**

(22) Filed: **May 16, 2017**

(80) **Hague Agreement Data**

Int. Filing Date: **May 16, 2017**
 Int. Reg. No.: **DM/096193**
 Int. Reg. Date: **May 16, 2017**
 Int. Reg. Pub. Date: **Nov. 17, 2017**

(30) **Foreign Application Priority Data**

Nov. 16, 2016 (KR) 30-2016-0055139

(51) LOC (11) Cl. **15-99**

(52) U.S. Cl.

USPC **D15/199**
 CPC **B25J 11/009** (2013.01)
